CLAIM

The ornamental design for a fabric covered claw clip as shown and described.

DESCRIPTION

FIG. 1 is a perspective view of a fabric covered claw clip, showing my new design.

FIG. 2 is a perspective view of the fabric covered claw clip.

FIG. 3 is a perspective view of the fabric covered claw clip.

FIG. 4 is a perspective view of the fabric covered claw clip.

FIG. 5 is a top view of the fabric covered claw clip.

FIG. 6 is a bottom view of the fabric covered claw clip.

FIG. 7 is a side view of the fabric covered claw clip.

FIG. 8 is a side view of the fabric covered claw clip.

FIG. 9 is a front view of the fabric covered claw clip; and,

FIG. 10 is a rear view of the fabric covered claw clip.

My hairstyling device design is characterized by a tube of fabric fed on to the claw clip.

1 Claim, 6 Drawing Sheets
